UNITED STATES PATENT OFFICE

2,572,213

ATOMIZER

Gregory Steinberg, Bayside, N. Y.

Application February 26, 1947, Serial No. 731,001

11 Claims. (Cl. 299—88)

1

The invention here disclosed relates to atomizers and particularly those of the small, portable type for carrying in the pocket, pocketbook, or the like.

Important objects of the invention are to provide a small size, neat appearing device of this character which when closed will be fully and safely sealed and which when released or unlocked will furnish, with very little effort, instant and effective atomization of liquids such as perfumes and medicinal preparations.

Special objects of the invention are to provide convenient, instantly operable and practical means for accomplishing the locking and unlocking of the device.

Particularly it is a purpose of the invention to prevent the sealing or closure means from contacting the spray nozzle and drawing out loose liquid in the pumping strokes furnishing the atomization.

Further special objects are to provide an atomizer construction of the character indicated which will be made up of relatively few, simple, rugged parts readily assembled, which can be produced at low cost and which in some instances will be self-aligning and hence not involve expensive machining and assembling operations.

Other desirable objects and advantages attained by the invention will appear in the course of the following specification.

The drawings accompanying and forming part of the specification illustrate certain present preferred embodiments of the invention. Structure and operation, however, may be modified and changed as regards the immediate illustration, all within the true intent and broad scope of the invention as hereinafter defined and claimed.

Fig. 1 in the drawings is a longitudinal sectional view of one of the atomizers, shown with the plunger released and ready for pumping action, the intermediate portion of the plunger rod shown broken away for lack of space;

Fig. 2 is a generally similar view taken on a different plane and showing the plunger at the bottom of its pumping stroke, with the nozzle sealing element spaced a definite distance away from the tip of the nozzle;

Figs. 3 and 4 are cross sectional views as on substantially the plane of lines 3—3 and 4—4, respectively, of Fig. 1;

Fig. 5 is a broken longitudinal sectional view showing the plunger fully depressed and secured in locked position, with the spray nozzle and vent tube fully sealed;

Figs. 6 and 7 are perspective views of the rotary plunger locking and releasing ring.

2

Fig. 8 is a broken vertical sectional view of portions of the cylinder, plunger and piston structure illustrating how these parts may be eccentric or off center either by design or accident, and will be operative in such relation;

Fig. 9 is a broken vertical sectional view illustrating a modified form of means for automatically effecting separation of the seal from the spray nozzle during pumping operations, the parts appearing as after release and automatically offset for pumping operations.

Fig. 10 is a side elevation of the latter construction, in the closed and sealed condition;

Fig. 11 is a cross sectional view as on substantially the plane of line 11—11 of Fig. 9.

Fig. 12 is a perspective view of the eccentric thrust member or washer.

The device consists in general of a small piston pump within a closely surrounding casing which provides the liquid chamber, with passages providing for atomization, and a ring rotatably mounted on the upper end of the casing and serving for locking and for releasing the plunger which actuates the piston of the pump.

25 The casing is shown as a tubular member 15 having a head, plug or body portion 16 secured in the upper end and having a plug 17 for liquid filling purposes screwed in the lower end of the same.

30 The top or body portion 16 is shown as annularly shouldered about the upper portion to provide between it and the surrounding wall of the barrel or casing, an annular groove or channel 18 rotatably receiving the inwardly shouldered, dependent skirt portion 19 of the control or locking ring 20.

35 This ring is shown as rotatably confined in this relation by a screw 21, Fig. 3, extending through an arcuate slot 22 in the skirt portion 19 of the ring into the body of the plug or top member 16.

40 The control ring 20 is shown in Figs. 1 and 10 as knurled or striated to provide a grip for the turning of this ring to the extent permitted by the securing and stop screw 21.

45 The pump structure is shown as made up of a cylinder 23 secured in the under side of the body member 16 and a piston 24 operating in said cylinder.

A spring 25, partly housed within the piston 50 and acting against the bottom 26 of the cylinder, thrusts the piston upward and a plunger rod 27 serves for forcing the piston downward or inward, under pressure of a finger applied to the knob, cap or head 28 on the upper, outer end of the plunger.

In Fig. 1 a small tube 29 is shown extending

from the lower end of the liquid chamber 30 surrounding the pump cylinder, up through the top member 16 and terminating in a spray nozzle 31.

A short and small diameter vent tube 32 is shown extending from the upper portion of the liquid reservoir chamber, up through the top member 16 and terminating at the top substantially on the same level as the nozzle 31.

In Fig. 2 an air tube 33 is shown extending from the lower portion of the pump cylinder up into an air passage 34 in the head 16 and which passage, as shown in Fig. 1, terminates in an upwardly inclined discharge outlet 35 directed radially outwardly over the top of the atomizing nozzle 31.

Small vent openings 36 up through the head 16, provide quick relief for air trapped in the upper end of the cylinder above the piston.

The pump operating knob 28 is shown hollow at the under side to accommodate a sealing gasket or washer 37 of rubber or other suitable resilient material, backed up by a loose metal washer 38 under tension of spring 39, the spring mounted sealing washer being confined in this relation by the in-turned lower rim 40 of this cap structure.

The parts are so designed and proportioned that with the plunger all the way down as in Fig. 5, the sealing washer 37 will be held firmly closed over the top of the nozzle 31 and the vent tube 32.

To hold the piston plunger in the fully closed and sealed position, Fig. 5, a locking pin 41 is provided in the present disclosure, sliding in a radial bore 42 in the top 16 and having a rounded inner end to engage in a more or less correspondingly rounded annular groove 43 in the piston plunger.

The locking pin 41 is controlled in its radial movements by the surrounding skirt portion 19 of the turn ring 20 and which is shown in Figs. 2, 3 and 7 as having an opening 44 to admit the outer end of the pin to release it from holding engagement with the plunger.

Additionally the skirt portion of the ring is shown as having another opening 45 to accept the spring pressed detent ball 46 in the unlocked or released position of the parts, Fig. 3.

The locking ring 20 is further shown as having an opening 47 to align with the spray nozzle 31 when the ring is in the release position shown in Fig. 1.

To effect an automatic separation or longitudinal extension of the parts, such as to prevent the seal from touching the nozzle during pumping operations, a spring 48 is shown in Figs. 1 and 2, engaged about the lower end of the plunger between an abutment washer or flange 49 on the plunger and the piston 24 to form an expansible and compressible coupling between the two.

This smaller diameter spring 48 is stiffer than the larger piston expansion spring 25 and enough so to act as a yieldable stop, preventing further downward movement of the piston button than that shown in Fig. 2 during normal pumping operations.

In such relation the sealing washer on the under side of the plunger button is supported well above the top of the nozzle 31, as shown in Fig. 2. This, however, does not limit the full inward stroke of the piston. It merely insures that at the end of the full compression stroke the sealing washer will be held separated from the

nozzle and hence not be wetted by contact therewith.

When, however, it is desired to close and seal the atomizer, it is merely necessary to press the plunger inward with sufficient additional force to overcome the stiffness of spring 48 and to turn the locking ring to force the holding pin 41 into engagement with the groove 43 in the plunger stem, Fig. 3. This may all be accomplished by one simple, combined inward thrusting and rotary motion on the plunger and securing ring.

Keeping the washer 37 clear of the nozzle 31 during the pumping stroke avoids drawing in particles of liquid up off the top of the nozzle and prevents spattering and objectionable wetness about the top of the nozzle both during pumping and under sealing conditions.

Leakage is prevented by the resilient washer being firmly and yieldingly pressed against both the nozzle 31 and the air vent tube 32 by the washer spring 39.

When the parts are closed and sealed as in Fig. 5, the operating knob or button 28 is substantially fully telescoped within the ring 20, closing the opening 47 through which the spray is discharged and leaving the device with no exposed or uncovered openings.

Other means may be provided for preventing the sealing element from contacting the nozzle during pumping operations, such as the structure shown in Figs. 9, 10 and 11, where the spindle 27a is of angular cross section and therefore held against rotation in sliding through the correspondingly shaped guide opening in the head 16, and the operating button 28 has a cam or screw engagement with such non-rotating spindle.

In Fig. 9 the spindle is shown as having a multiple or high pitch screw thread 50 on its upper end engaged by a corresponding nut 51 in the operating button.

The spray discharge opening 47a is shown opened up through the top of the locking ring or sleeve 20 to admit, in the fully closed and sealed relation of the parts, Fig. 10, a lug or pin 52 projecting from the side of the button.

Then when the ring 20 is turned to unlock the spindle, in that same act the cap will be turned relative to the spindle and thereby through the cam or screw connection 50, 51, raised or lifted away from the top of the nozzle.

The screw thread connection indicated at 50, 51, is of the self-locking type so that the button will normally stand in the same position to which it has been turned by the locking ring 20 and consequently be in position for the lug 52 to enter the open slot 47a when the button is pressed to actuate the atomizer. This engagement of the lug in the open notch in the ring insures that the parts can be immediately locked closed by simply turning the locking ring in the proper direction when the plunger is pushed all the way down.

In both forms of the invention considered the operating button is automatically extended upon unlocking the plunger, as illustrated in Figs. 2 and 9, so that thereafter the sealing washer 37 will not contact the spray nozzle 31 in the pumping action of the device, and this separation or extension is accomplished without limiting the stroke imparted to the piston. In each instance the piston can be pushed all the way down to the bottom of the cylinder to make a full stroke, without touching the sealing element, to the end of the nozzle. When, however, the locking ring is turned to lock the parts the sealing washer will

be forced down firmly over the top of the nozzle, substantially as indicated in Fig. 5.

The pumping cylinder may be arranged concentrically or eccentrically within the casing.

In some instances the over-all diameter can be reduced by disposing the pump cylinder eccentrically, substantially as represented in Figs. 8, 9 and 11.

In Fig. 8 the spindle or piston rod 27 is shown as eccentrically disposed within cylinder 23. In such case the abutment washer 49 may be rotatably engaged with the end of the spindle, as represented at 53.

The same is generally true as to the construction shown in Figs. 9, 11 and 12, where the thrust washer 49 is rotatably connected with the lower end of the spindle 27a at 53 so as to leave these parts free to adjust themselves to the eccentricity. In the latter construction the thrust member 49 bears directly on the piston 24 instead of through the medium of an interposed spring, such as at 48 in Fig. 1.

By arranging the pump cylinder 23 eccentrically within the casing 15, space may be obtained at one side; for example, for a larger size liquid tube 29 and the space thereby lost at the opposite side may still be large enough for the smaller size vent tube 32.

Thus the parts may be placed to best advantage without increasing the over-all diameter of the device.

The construction and arrangement of parts enables the device to be made up in particularly small, attractive form. While fully sealed when not in use, it is always ready for instant use. The act of unlocking it automatically effects a separation of the closure from the spray nozzle so that even with the full pumping stroke the closure will not contact the nozzle. Hence the closure will be kept dry and ready to seal the nozzle as soon as the pumping operations are completed, and it will then completely close the nozzle without leaving any surface liquid about the same. The final act in closing the device, involving the lowering of the knob of the plunger to compress the heavier or stronger spring in the first instance or turn the head on its screw mounting in the second instance, serves to yieldingly set the closure firmly down over the ends of the nozzle and the air vent tube. The locking pin assists in this operation, the inner, rounded end of the same acting as a cam in the annular groove in the plunger to force the plunger inward to its lowest position in the cylinder. In this final position the spray outlet in the side of the locking ring is closed by the plunger knob passing down inside the ring. Thus in the final position there are no uncovered openings. The presence of the opening in the ring, however, is desirable as indicating the location of the spray nozzle, so that in unlocking the device the person may observe the point of issuance of the spray and use the device accordingly.

The washer 49 may have a loose fit in the cylinder so as to operate as a guide for the lower end portion of the spindle 27. This washer may be screwed in position over the lower, reduced, screw threaded end portion of the spindle, as indicated at 70. The spindle 27 may then be inserted from the bottom of cylinder 23 up through the head 16. The piston 24 may then be inserted in the cylinder with the coupling spring 48 above it and the piston raising spring 25 below it, after which the disc 26 for closing the lower end of the cylinder may be secured as by screwing it into

the lower end of the cylinder, by soldering, brazing, or otherwise fastening it in place. After this the knob or operating button 28 carrying the sealing washer 31 may be screwed onto the projecting upper end of the spindle.

The second form of the invention illustrated in Figs. 9 and 10 may be assembled from the bottom in a generally similar manner.

In both forms the piston has a free floating action in the cylinder, between the coupling spring 48 and lifting spring 25 in the first form, and between the abutment washer 49 and the lifting spring 25 in the second form.

This floating piston form of construction avoids the necessity for extreme accuracy in the alignment of parts, permitting misalignment or a considerable degree of eccentricity as between the plunger and piston without tendency of the piston to jam in the cylinder.

20 The air compressed by the piston is full utilized because the piston spring 25 in its compressed position occupies the annular space within the piston. The piston at such time may actually engage the bottom wall 26 of the cylinder, as indicated in Fig. 2. The latter feature is of further advantage in stopping the piston at a point to prevent total compression of spring 25. This avoids straining or "tiring" the spring, insuring maintaining it in condition for most effective operation.

25 In the first form of the invention, Fig. 1, the relative separation and lifting of the closure away from the nozzle is automatically effected substantially simultaneously with the releasing of the plunger by the locking ring, whereas in the second form of the invention, Fig. 5, the closure separation may be considered as a synchronized step or stage in the action of releasing the piston plunger. In both constructions the closure separation may therefore be considered as a definite part of or stage in the releasing action of the plunger.

30 While, because of the particularly compact arrangement of parts, the invention is of special importance for small size atomizers, it will be appreciated that it may be used with advantage for table model and other size atomizers.

What is claimed is:

1. An atomizer comprising a casing having a spray delivery nozzle at the top, an air pump in said casing for supplying the atomizing force for said nozzle, said air pump including a cylinder, a piston operating in said cylinder, a plunger for actuating the piston projecting from the top of the casing and having an operating head on the upper end of the same, a closure for the nozzle carried by said operating head and engageable with the nozzle when the plunger is fully lowered in the casing, releasable means for holding the plunger lowered with said closure in engagement with the nozzle and means for automatically effecting limited, further separation of said closure in respect to said piston upon release of said holding means, to prevent engagement of the closure with the nozzle during normal, full-length pumping strokes of the plunger and piston and including an extensible and collapsible connection interposed at a point between said piston at the lower end of the plunger and said operating head at the upper end of the same operative, when released, to effect pumping action of the piston with the closure raised clear of engagement with the nozzle but manually collapsible and arranged to be held collapsed by said holding means to effect sealing engagement of the closure with the nozzle.

2. An atomizer comprising a casing having a spray delivery nozzle at the top, an air pump in said casing for supplying the atomizing force for said nozzle, said air pump including a cylinder, a piston operating in said cylinder and a plunger for actuating the piston projecting from the top of the casing, a closure for the nozzle carried by said plunger and engageable with the nozzle when the plunger is fully lowered in the casing, releasable means for holding the plunger lowered with said closure in engagement with the nozzle and means for effecting limited, further separation of said closure in respect to said piston upon release of said holding means, to prevent engagement of the closure with the nozzle during normal, full-length pumping strokes of the plunger and piston and said means for effecting such further separation including a yielding but stiff spring connection between the plunger and piston and there being a spring for lifting the piston but less stiff than said connecting spring.

3. An atomizer comprising a casing having a spray delivery nozzle at the top, an air pump in said casing for supplying the atomizing force for said nozzle, said air pump including a cylinder, a piston operating in said cylinder and a plunger for actuating the piston projecting from the top of the casing, a closure for the nozzle carried by said plunger and engageable with the nozzle when the plunger is fully lowered in the casing, releasable means for holding the plunger lowered with said closure in engagement with the nozzle and means for effecting limited, further separation of said closure in respect to said piston upon release of said holding means, to prevent engagement of the closure with the nozzle during normal, full-length pumping strokes of the plunger and piston and said means including an inclined cam connection between the closure and plunger, the plunger having a non-rotative sliding movement in the top of the casing and the holding means aforesaid being operative to shift said cam connection for the purpose described.

4. An atomizer comprising a casing having a spray delivery nozzle at the top, an air pump in said casing for supplying the motive force for atomization, said air pump including a cylinder, a piston operating in said cylinder and a plunger for actuating the piston projecting from the top of the casing, an operating head on the upper end of said plunger, a closure for the nozzle at the under side of said operating head, a ring for securing the plunger rotatably adjustable on the upper end of the casing and means for automatically effecting limited, further separation of said operating head and piston upon releasing movement of said securing ring on the casing and including a stiff connecting spring between the plunger and piston, there being a less stiff spring in the cylinder for raising the piston and plunger.

5. An atomizer comprising a casing having a spray delivery nozzle at the top, an air pump in said casing for supplying the motive force for atomization, said air pump including a cylinder, a piston operating in said cylinder and a plunger for actuating the piston projecting from the top of the casing, an operating head on the upper end of said plunger, a closure for the nozzle at the under side of said operating head, a ring for securing the plunger rotatably adjustable on the upper end of the casing and means for automatically effecting limited, further separation of said operating head and piston upon releasing movement of said securing ring on the casing,

including a fast screw connection of the self-locking type between said operating head and the upper end of the plunger, the plunger having a non-rotative, sliding movement up through the top of the casing and said securing ring being engageable with said operating head during the releasing movement of the securing ring to effect turning of the operating head on said screw connection.

6. An atomizer comprising a liquid containing casing, an air pump including a cylinder mounted in said casing, a piston operating in said cylinder and a plunger projecting up through the top of the casing, a liquid tube extending from within the casing and terminating in a spray delivery nozzle on top of the casing, a locking ring rotatably adjustable on the upper end of the casing, an operating head on the upper end of the plunger, a sealing washer at the under side of said head for closing engagement with the top of the nozzle, a spring within the cylinder for lifting the piston and plunger, a stiffer spring interposed between the plunger and the upper side of the piston and means operable by said locking ring for securing the plunger in fully lowered position with said relatively stiff spring compressed and the operating head lowered with the sealing washer in closing engagement with the top of the nozzle.

7. An atomizer comprising a casing having an annular groove in the upper end of the same, a ring having a reduced lower end portion rotatably engaged in said annular groove, a cylinder within the casing, a piston operable in said cylinder, a plunger for actuating said piston projecting up through the top of the casing, said plunger having a recess in the side of the same, a pin radially slidable in the top of the casing into engagement with said recess, the reduced skirt portion of the ring being engageable with the outer end of said pin to thrust the same inward into holding engagement in said recess in said plunger and provided with an opening to permit outward plunger releasing movement of said pin, an operating head on the upper end of said plunger, said head being telescopically engageable in the upper portion of said ring, a sealing washer carried by said head at the under side of the same, a liquid tube extending from within said casing and terminating in a spray nozzle on top of the casing in position for engagement by said sealing washer in the fully depressed position of the operating head.

8. In an atomizer having a spray nozzle, a pump plunger carrying a sealing element for engagement with the nozzle when the plunger is fully depressed, that improvement which comprises the provision of a relatively stiff spring which will become effective as soon as the piston is released for pumping action to separate the closure element from the nozzle and will hold said element spaced from the nozzle in the full length pumping strokes of the plunger but may be compressed to permit the closure element again to lower into sealing engagement with the nozzle at the end of the pumping operations.

9. An atomizer comprising a casing having a pump cylinder and a spray delivery nozzle actuated from said cylinder, an operating plunger projecting from the cylinder, a floating piston operating in said cylinder, a spring for lifting said piston and a floating operating connection between the plunger and piston, including a spring interposed between and forming the sole

means of connection between the plunger and piston.

10. An atomizer comprising a casing having a pump cylinder and a spray delivery nozzle actuated from said cylinder, an operating plunger projecting from the cylinder, a floating piston operating in said cylinder, a spring for lifting said piston and a floating operating connection between the plunger and piston, including a spring interposed between and forming the sole means of connection between the plunger and piston, said piston having a cavity in the top of the same enclosing said connecting spring and an annular cavity in the bottom of the same receiving the piston lifting spring.

11. An atomizer comprising a casing having a pump cylinder therein, a piston operating in said cylinder, a spring for lifting said piston in the cylinder, a stop limiting the downward movement of the piston in the cylinder to a position where said lifting spring is still under expansion, a plunger operating down through the top

of the cylinder and a coupling spring between said plunger and piston, said coupling spring being stiffer than said piston lifting spring and arranged to thrust the piston to the limit of its stopped movement without substantial compression.
